INVENTOR:

Oliver S. Wright,
BY Franey & Paul
ATTORNEYS.

UNITED STATES PATENT OFFICE.

OLIVER S. WRIGHT, OF PHILADELPHIA, PENNSYLVANIA.

TEXTILE-TREATING MACHINE.

Application filed August 4, 1922. Serial No. 579,552.

To all whom it may concern:

Be it known that I, OLIVER S. WRIGHT, a citizen of Canada, residing at Philadelphia, county of Philadelphia, and State of Pennsylvania, have invented certain new and useful Improvements in Textile-Treating Machines, whereof the following is a specification, reference being had to the accompanying drawings.

10 This invention relates to textile treating machines and more especially to clothes washing machines of the power operated type, and the principal object of the invention is to provide a non-complex and efficient driving or power translating mechanism adapted to be operated by an electric motor to oscillate the textile container forming part of the machine and which may be of any approved or desired type.

15 Another object of the invention is to provide improvements in textile treating machines of the type embodying an oscillatory drum, whereby the drum may be readily inserted in proper location in the tub, or removed therefrom and upon its replacement in the tub to be readily connected in operative relation to the power driving means, the means whereby the connection is made according to the present invention consisting of a novel form of clutch device which is adapted to be locked by a lateral shifting motion of the drum.

20 Another object of the invention is to provide a novel form of wringer operating mechanism which is particularly adapted for association with the operating mechanism for the drum so as to be driven at will from the prime mover common to both the associated mechanism and the wringer.

25 These and other objects are accomplished by what I now regard as the most preferred embodiment of my invention from among other possible forms and arrangements embraced within the spirit of the invention and comprehending improvements in general details of construction and the arrangement of correlated parts to be hereinafter set forth and particularly pointed out in the appended claims.

30 In the accompanying drawings Fig. I is a view in side elevation of a textile treating machine embodying my improvements and

showing one side wall broken away to disclose interior details.

Fig. II, is a view in enlarged vertical section taken on the line II-II of Fig. I.

Fig. III, is a view of the drum in end elevation illustrating one of the trunnions and a shifting means therefor.

Fig. IV, is a detail view in enlarged section taken on the line IV-IV of Fig. III.

Fig. V, is a view in side elevation of the driving mechanism for the wringer.

Fig. VI, is a view in section taken on line VI-VI of Fig. V.

Fig. VII is a vertical sectional view taken through the textile treating machine and looking towards the left hand of Fig. I.

With reference to the drawings, 10 indicates a tub of any approved construction supported upon a frame work 11 and including an upright rear wall 12 which is selected to provide a support for the driving mechanism. An angular bracket 13 is fixed to the outer surface of the wall 12 for the purpose of supporting upon a horizontal ledge an electric motor 14 having a protruding shaft 15 which extends into an opening formed in the wall 12 for the purpose of connection to a gearing or the like forming part of the driving mechanism and which may consist of a worm 16 which is thus located interiorly of the tub and in meshing engagement with a worm wheel 17. The wheel 17 may be supported upon a stub shaft 18 in turn journaled in a sleeve 19, the latter extending through aligned openings formed in the opposing flanges 20 of a channel bracket 21 which is affixed to the bracket 13 by spot welding or in any other approved fashion.

35 In this manner the driving gear 16, 17 and motor 14 are fixed in proper meshing relation and are supported as a unit upon the wall 12 of the tub. A pin 22 projects eccentrically from the face of the worm wheel 17 and receives the perforated end of a pitman rod 23, the opposite end of which hugs the adjacent wall of the tub 10 and extends toward the center of rotation of a closed drum or textile container indicated comprehensively by the numeral 24 and which may be of any approved design or construction, being shown in the present in-

stance as cylindrical in formation with opposed flat sides in which openings—not shown—are provided for the insertion of material to be treated as will be obvious to anyone acquainted with the art. The drum is preferably formed of perforated sheet metal as fragmentarily indicated in Fig. IV to permit the free circulation of water therethrough.

10 The drum 24 is further provided at its ends with a pair of aligned trunnions 25 and 26, the former resting in an opening formed in a depending bracket 27 secured to the inner face of the adjacent wall of the tub 10, said bracket being formed with an under hanging semi-circular lip 28 upon which the trunnion 25 rests so as to permit the drum 24 to be readily lifted from the tub 10 when desired. Also fitted within the opening of 15 the bracket 27 in alignment with the trunnion 25 is an axial stud 29 which extends laterally from one end of a link 30, the opposite end of said link having a laterally projecting stud 31 which is seated in the perforated 20 end of the aforesaid pitman rod 23. The trunnion 25 is formed upon the face of a plate 32 which is secured to the end wall of the drum 24 and is provided at one end with an opening 33 adapted to receive the stud 31 when the latter is brought into registration therewith, said opening however being slightly larger in diameter than the diameter of the stud 31 for a purpose to be presently noted.

35 The meeting faces of the trunnion 25 and stud 29 are cut away at opposite sides to form complementary interlocking lugs 34, and recesses the relation of which are such as to permit interlocking engagement only 40 when the stud 31 is brought opposite the opening 33. To insure rigidity of structure the bracket 27 is riveted to the wall of the tub 10 through the medium of an angle bar 35 which is applied to the outer face of the 45 tub wall and through the medium of rivets or other fastening means 36 which also serve to secure one end of a depending finger 37, the opposite end of which rests against the outer surface of the tub wall at a point 50 directly opposite the stud 29, so as to prevent dislodgment of the stud from the bracket by outward flexing of the tub wall which in many instances may be sheet metal. The opposite trunnion 26 rests in a bifurcated bracket 38 which is supported upon a channel bar 39 extending horizontally and hugging the inner surface of the adjacent tub wall. The bracket 38 supports for rotation one end of a shaft 40 which is housed 55 within the flanges of the channel bar 39, projects through the end wall of the tub and is provided with a right angular extension 41 forming a handle whereby the shaft may be rocked. A finger 42 is fixed to the inner 60 end of the shaft and its extremity is seated

within a notch 43 formed in the underside of the trunnion 26 so that the drum may be shifted axially by rocking the shaft through the medium of its handle portion.

Rotation of the motor 14 is transmitted 70 through the meshing gears 16 and 17 and translated into oscillatory motion for transmission to the drum 24 so that the latter is rocked and the material contained therein thoroughly agitated. It will be noted that 75 the drum 24 may be readily lifted from the tub for the purpose of cleaning or repair by merely rocking the arm 41 so as to shift said drum laterally or in other words to mutually disengage the studs 25 and 29 and to withdraw the stud 31 from the opening 33. The drum 24 may now be lifted as the supporting elements 28, 38 for the trunnions 25, 26 are open at the top and readily permit release of said trunnions therefrom.

80 After the drum 24 is replaced the arm 41 is again rocked to shift said drum axially into position wherein the studs 25 and 29 are interlocked, having previously adjusted the drum by rocking in either direction with the hand until the stud 31 is brought opposite the opening 33, so that the stud may then enter the opening. In this manner the drum 24 is locked to the driving mechanism 85 at two places namely; centrally at the trunnion 25 and eccentrically at the stud 31. Owing to the enlarged aperture of the opening 33 with respect to the stud 31 a slight loss of motion is permitted between 90 the drum and the stud 31, limited by engagement of the latter with the walls of the opening 33, so that at the end of each period of oscillation the drum 24 may be gradually brought to rest before reversing 95 its movement thus avoiding any strain upon the motor and gearing.

100 It will be apparent that the driving mechanism described may be adapted not only to washing machines but to any other apparatus embodying an element designed 105 to be rotated or oscillated and which entails separation from the remainder of the apparatus or disengagement from the driving mechanism. In lieu of the specific drum shifting mechanism described I may employ 110 any other type of mechanism found suitable or convenient for the purpose.

115 The present invention also embodies a novel form of operating means for a clothes wringer and I have disclosed a preferred 120 form of mechanism which is adapted particularly for use in connection with the driving mechanism described above. With reference to Figures V and VI wherein I have illustrated the wringer mechanism, 45 indicates a bracket which may be of any desired configuration and applied to the inner face of the tub wall 12, and is preferably held by means of the same fasteners 125 which secure the motor bracket 13. Sup-

ported in the bracket 45 is a sleeve 46 enclosing a shaft 47, the lower end of which is supplied with a beveled gear 48 in meshing relation with a beveled gear 49 applied 5 or cast to one side face of the worm wheel 17. The upper end of the sleeve 46 protrudes beyond the edge of the tub 10 and supports a block 50 which is freely rotatable about said sleeve and which rests upon the bracket 45. An arm 51 extends from the block 50 for the purpose of supporting the clothes wringer indicated at 52, one of the rolls of which is supplied with an operating shaft 53, extending toward the block 50 and 10 entering a housing 54 forming part of said block 50 designed to contain a set of reversing gears which includes a beveled gear 55 fixed to the upper end of the shaft 47, and a pair of gears 56 which are slidably 15 mounted upon the shaft 53 and are connected by means of a sleeve 57, whereby they may be shifted in unison to engage alternately the gear 55.

The shifting of the gears 56 is brought 20 about by means of a pair of oppositely extending fingers 58 which are carried by a shaft 59 mounted in the side wall of the casing 54 and which is rocked by means of a handle 60. Thus, the wringer mechanism 25 may be swung around the sleeve 46 as a center of rotation and brought into any desirable position while retaining its mechanism in operative relation to the drive at all times. The wringer mechanism may 30 however be held in any adjusted position by means of a set screw 61 which is threadedly engaged in a lateral boss formed on the block 50, the set screw engaging the sleeve 46. The motor and wringer drive 35 being thus mounted at opposite sides of the tub wall effect a mutual balance which avoids lateral strain upon the wall.

Thus, the power of the motor 14 is transmitted through the gearing 48 and 49 to 40 the shaft 47 and through the reversing gears 56 to the roller of the wringer, directional rotation of which may be altered by rocking the arm 60. The wringer may be disconnected from the driving mechanism by 45 centralizing the gears 56 so that neither will be in meshing engagement with the gear 55. Owing to the fact that the gears are all 50 located within the tub 10 they are lubricated by the soapy water and are moreover 55 thus guarded or hidden so as to prevent injury or accident which might occur if the gears were located exteriorally.

Owing to the provision of the clutch mechanism it will be seen that the drum 24 may 60 be brought into such a position that its flat side is level with the top edge of the tub 10, thus making it more convenient to insert or remove the clothing. The tub 10 may be provided with a flat cover if desired

with a view to making the machine available as a table or support.

Having thus described my invention, I claim:

1. A machine for treating textiles comprising a tub including a vertical wall, an oscillatable container journaled therein, a bracket secured exteriorly to the tub wall, a motor supported by the bracket and having its shaft extended through an opening in said wall, an extension from the bracket 70 into the tub to journal a direct drive from said motor, and a power translating connection between the direct drive and container whereby the latter is oscillated.

2. In a textile treating machine, an enclosure, an oscillatable container having trunnions mounted therein, a motor rigidly supported exteriorly of the enclosure, means directly driven by said motor for co-action with one of said trunnions to oscillate the 85 container, means whereby the container may be laterally shifted for removal and replacement, and means serving to lock the container in operative connection with the driving means subsequent to replacement. 90

3. In a textile treating machine, an enclosure, an oscillatable container therein, trunnions extending from the container, one of which is segmentally cut away, means supporting the trunnions in the enclosure, 95 a driving mechanism and a power translating linkage having a segmental stud effective upon axial shifting movement of the container to establish an operative connection with the driving mechanism. 100

4. In a textile treating machine, an enclosure, a container oscillatably mounted therein by a pair of axially aligned trunnions, one of said trunnions being cut away 105 to provide a segmental stud and the other circumferentially notched, brackets within the enclosure supporting the trunnions, an operating mechanism including a driven member having a segmental stud mounted in one of said brackets in alignment with the cut away trunnion, and means co-operative with the notched trunnion to effect a lateral shifting of the container in one direction to bring said studs into locking and power transmitting engagement by the driven 110 member. 115

5. In a textile treating machine a rotatable container adapted for lateral movement, and a power translating mechanism including a member disposed adjacent the container and adapted when the latter is shifted laterally to engage the container at a point coinciding with the axis of rotation and at a point eccentrically disposed to impart motion to said container. 120

6. In a textile treating machine, a driving mechanism including a member oscillatable about one of its ends, a container having ca- 125

paceity for lateral movement, means for laterally shifting the container, means for connecting said container with the axis of oscillation of the aforesaid member, and 5 means for connecting the free end of said member to the container at a point eccentric to its axis of rotation.

7. In a textile treating machine, a driving mechanism including a pivotal member having its free end adapted for orbital rotation, a stud provided at the free end of said member, an oscillatable container having capacity for lateral movement, means adapted upon lateral movement of said container to lock the latter to the pivotal member at its axis of rotation, and said container having an opening adapted to receive the aforesaid stud, whereby the pivotal member is engaged with the container at 20 axial and eccentric points.

8. In a textile treating machine, an enclosure, a container mounted therein including trunnions, brackets supporting said trunnions, a link journaled in one of said brackets and having laterally projecting studs, means for effecting a locking connection between said studs and the container, and a power translating mechanism operatively connectable with the free end of the 25 link for imparting oscillatory motion thereto.

9. In a textile treating machine, an enclosure, a container mounted therein by

trunnions, brackets supporting said trunnions and permitting lateral movement of 35 the container, a power translating mechanism, and a manually actuatable shifter means co-operative with one trunnion to move the container and effect an interlocking connection between the other trunnion and the 40 power translating mechanism, and vice versa.

10. In a textile treating machine, an enclosure, a container mounted therein having a pair of trunnions one of which is circumferentially notched, brackets supporting the trunnions, a shaft, a finger carried by the shaft in operative engagement with the notched part of the aforesaid trunnion for shifting the container laterally, a driving mechanism, and means effective upon said shifting movement to operatively connect the other trunnion and container with the driving mechanism.

11. In a textile treating machine, an oscillating container having an eccentric recess, a power translating mechanism including a member entering said recess of a lesser diameter than the recess so as to permit lost motion between said member and container when reversing the direction of movement of the container.

In testimony whereof, I have hereunto signed my name at Philadelphia, Pennsylvania, this third day of August, 1922.

OLIVER S. WRIGHT.
